UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

LOOPER-OPERATING MECHANISM FOR SEWING MACHINES.

Application filed October 1, 1921. Serial No. 504,644.

To all whom it may concern:

Be it known that I, ANDREW B. CLAYTON, a citizen of the United States, residing at Union, in the county of Union and State of New Jersey, have invented certain new and useful Improvements in Looper-Operating Mechanisms for Sewing Machines, of which the following is a specification, reference being had therein to the accompanying drawings.

This invention relates to sewing machines and particularly to the looper-operating mechanism of chain-stitch machines.

In looper-operating mechanisms of the type wherein an inclined pin-and-sleeve connection is employed between the looper-actuating shaft and the looper for moving the latter in the usual elliptical path, as disclosed for example in the patent to Albert H. De Voe, No. 1,085,801, February 3, 1914, considerable difficulty has been encountered in machining the parts to the degree of accuracy required for successful assemblage and operation. Where, as in the machine of the De Voe patent, the inclined pin and sleeve are held in fixed angular relation with their respective supporting elements, it is necessary that a high degree of accuracy be attained in the manufacture of the pin-carrier and sleeve element and in the location of the various centers, otherwise the parts when assembled will cramp or bind upon one another, thereby causing excessive wear. Furthermore, even if the pin is set at the correct angle of inclination, a high degree of accuracy must be attained in locating the axis of the looper-carrier relative to the main-shaft, else the position of the looper-point relative to the needle at the time the looper begins its loop-seizing stroke, will not be correct. If the position is incorrect due to errors in manufacture, no adjustments are provided in prior constructions of this character whereby such position may be corrected.

An object of the present invention therefore is to provide a looper mechanism of the class described with adjustments of such character that errors in manufacture may be readily compensated for and, further, that the point of the looper may be set to the correct distance from the needle so as to seize the needle-loop at the instant the latter has expanded to the proper size.

Another object of the invention is to provide for the adjustment of the side throw or so-called "needle-avoiding" motion of the looper, so that the extent of such motion may be varied to suit the particular needle used; it being generally understood that the larger the diameter of the needle the greater should be the side throw of the looper.

In the accompanying drawings, Fig. 1 is a fragmentary front side elevation of the sewing machine embodying the invention. Fig. 2 is a fragmentary front end elevation of the same. Figs. 3 and 4 are views of the looper mechanism modified by the addition of a further adjustment for varying the side throw or "needle-avoiding" movement of the looper and illustrating the effect of one of the primary adjustments. The needle and main-shaft occupy the same positions in Figs. 3 and 4. Fig. 5 is a perspective view of the eccentric strap element shown in Figs. 1 and 2. Figs. 6 and 7 are detail perspective views of parts of the looper mechanism, and Fig. 8 is an elevation of the modified form of eccentric strap and sleeve members shown in Figs. 3 and 4.

In the embodiment of the invention illustrated for the purposes of the present disclosure 1 represents the bed-casting of a machine of the type illustrated in said De Voe patent. Journaled in the bed 1 is the rotary main-shaft 2 on which is fixed the looper-actuating eccentric 3, formed at one end with the integral flanged collar 3^a through which passes the usual set-screws 3^b. The machine is provided with the usual reciprocating needle 4, presser-foot 5 and feed-dog 6 which are constructed and operated in the usual manner.

Cooperating with the needle 4 is the looper 7 which, in the particular machine illustrated, is fixed to the looper-carrier arm 8 secured by the screw 9 to the grooved block 10 on the sleeve 11 which is mounted on a fixed horizontal looper-supporting pin 12 for rocking and endwise sliding movements. The pin 12 is preferably mounted in substantial parallelism with the main-shaft 2.

The sleeve member 11 of the looper-carrier is formed on its side remote from the main-shaft 2 with a boss 13 which is provided with an aperture 14 transversely of and in non-intersecting relation with the

axis of said sleeve member. The aperture 14 affords a socket for the pin 15 which is formed at one end with the transverse head 16. The head 16 is apertured at 17 to provide a socket for the inclined pin 18 which latter is fixed in the head 16 by set-screws 19. The pin 18 enters the sleeve 20' carried by and tangentially of the eccentric strap 20 embracing the eccentric 3. The sleeve 20' may be formed integral with the eccentric strap 20 as illustrated in Figs. 1, 2 and 5 and in said De Voe patent, or may be constructed separately from the strap 20 and adjustably pivoted to the latter, as shown 10 in Figs. 3, 4 and 8, so that its angle of inclination to the axis of the main-shaft may be altered to vary the degree of needle-avoiding motion imparted to the looper. To this latter end the strap 20 may be formed 15 with a seat 20^a having an aperture which receives the pivot pin 20^c on the sleeve member; such member being also provided with the oppositely disposed ears 20^d having slots 20^e curved concentric with the pin 20^c and 20 entered by screws 20^f which are threaded into the eccentric strap 20.

The pins 18 and 15 are disposed at an angle to one another and the latter is adjustably secured in the socket 14 by means of 30 set-screws 21. The eccentric strap 20 is confined on the eccentric 3 between the flanged collar 3^a, previously referred to, and a second flanged collar 3^c formed integral with the usual feed-lift eccentric 3^d, described in said De Voe patent.

By mounting the inclined pin 18 so that its inclination to the shaft 2 may be varied or, in other words, by adjustably swivelling the pin 18 transversely of the pin 12 or shaft 2, it may readily be set to line up with the inclined sleeve 20' and operate without binding or cramping. Furthermore, the point of the looper may be shifted relative to the needle-path, without disturbing 45 the timing of the reversal of motion of the looper relative to that of the needle, by adjusting the pin 15 lengthwise of the socket 14, as shown in Figs. 3 and 4; a slight lengthwise movement of the pin 15 effecting 50 a relatively large shift of the point of the looper. The needle and looper may thus continue to reverse their respective motions simultaneously, regardless of the foregoing adjustment; the looper beginning its advancing stroke as the needle begins its up-stroke, as is desirable in insuring entry of the looper loop by the needle on the down-stroke of the latter. This adjustment 55 enables the looper point to be set by a suitable gauge to the correct distance from the needle when the looper is beginning its loop-seizing stroke and the needle is beginning its up-stroke.

The lateral working position of the looper 60 is determined by the setting of the eccentric

3 lengthwise of the main-shaft 2, while the time of reversal of the motion of the looper is determined by the position of the eccentric 3 circumferentially of the main-shaft 2.

It will be evident that in the form of 70 construction illustrated in Figs. 3, 4 and 8, the angle of inclination of the pin-and-sleeve connection 18, 20' to the shaft 2 may be varied, and the amplitude of needle-avoiding motion of the looper altered, by 75 loosening the screws 21 and 20^c and swinging the elements of the pin-and-sleeve connection about the respective pivots 15 and 20^c to the desired extent. After this adjustment is made, the looper should be set 80 to the correct lateral position relative to the needle by adjusting the eccentric 3 longitudinally of the main-shaft. It is to be understood, however, that it is not essential to the invention, in certain aspects, that 85 both members of the pin-and-sleeve connection be adjustable on their respective carrier members. It is only when it is desired to incorporate in the machine a provision for adjusting the amplitude of the needle-avoiding movement of the looper that both 90 of such members are mounted for pivotal adjustment.

The looper 7, as shown, is of the non-thread carrying type. It is to be understood, however, that the present improvement is useful in driving loopers of any of the usual types designed to perform loop-seizing and needle-avoiding movements.

I am aware of the patent to Onderdonk No. 679,906, of August 6, 1901, disclosing a looper driving mechanism including a looper-driving pin which is inclined to the looper-driving shaft. In the Onderdonk construction, however, the axis of the inclined pin must intersect the respective axes of the main-shaft and looper-carrier, thereby necessitating the making of two adjustments when it is desired to alter the angle of inclination of the pin. I do not claim broadly the use of an adjustably inclined pin in a looper-drive.

Having thus set forth the nature of the invention, what I claim herein is—

1. In a looper mechanism, in combination, a looper driving shaft, an eccentric thereon, an eccentric strap, a looper-support, a looper having rocking and sliding movement on said looper-support, and a pin-and-sleeve sliding connection disposed between said eccentric strap and looper and inclined to said looper-driving shaft, one of the elements of said inclined pin-and-sleeve connection being adjustable transversely of the axis of rocking movement of the looper-carrier to alter the position of the looper point.

2. In a looper mechanism, in combination, a looper, a looper-carrier mounted for rocking and sliding movements, an actuat-

ing shaft, an eccentric thereon, a strap embracing said eccentric, a sleeve secured to said strap and having its axis in non-intersecting relation with and at an acute 5 angle to the axis of the actuating shaft, and a pin mounted on said looper-carrier for pivotal adjustment whereby it may be readily set to line up with said sleeve.

3. In a looper mechanism, a looper driving shaft, a looper mounted to perform a rocking movement transverse to said shaft and a sliding movement parallel to said shaft, an eccentric on said shaft, an eccentric strap, and a pin-and-sleeve sliding connection between said looper and said eccentric strap, one of the elements of said connection being bodily adjustable toward and from the axis of rocking movement of said looper.

4. In a looper mechanism, a looper driving shaft, a looper mounted to perform a rocking movement transverse to said shaft and a sliding movement parallel to said shaft, an eccentric on said shaft, an eccentric strap, and a pin-and-sleeve sliding connection between said looper and eccentric strap, one of the elements of said connection being pivotally adjustable toward and from the axis of rocking movement of said looper.

5. In a looper mechanism, a looper driving shaft, a looper mounted to perform a rocking movement transverse to said shaft and a sliding movement parallel to said shaft, an eccentric on said shaft, an eccentric strap, and a pin-and-sleeve sliding connection between said looper and eccentric strap, one of the elements of said connection being both bodily and pivotally adjustable relative to the axis of sliding movement of the looper.

40 6. In a looper mechanism, in combination, a looper driving shaft, a looper-support, a looper mounted for rocking and sliding movements on said looper-support, an eccentric on said shaft, an eccentric strap, and a pin-and-sleeve sliding connection between 45 said eccentric strap and looper adjustable toward and from the axis of rocking movement of the looper.

7. A looper mechanism having, in combination, a looper-driving shaft, an eccentric thereon, an eccentric strap, a looper, a looper-supporting shaft, and a pin-and-sleeve sliding connection between said eccentric strap and said looper, one of the elements of said connection being adjustably swivelled transversely of the axis of said looper-supporting shaft so as to line up with its mating element.

8. A looper mechanism having, in combination, a looper, a looper-support on which the looper is mounted for loop-seizing and sidewise movements, an actuating eccentric, and a pin-and-sleeve sliding connection disposed between said looper and eccentric and inclined to the axis of rotation of the latter, and means permitting adjustment of the angle of such inclination of the pin-and-sleeve connection to alter the amplitude of said sidewise movement.

9. A looper mechanism having, in combination, an actuating eccentric, an eccentric strap, a sleeve mounted on and transversely of the axis of said eccentric strap, means whereby said sleeve may be adjusted to vary the angular relation of its axis to the axis of said eccentric, a looper mounted for loop-seizing and sidewise movements, and an adjustable pin connected to move with said looper and entering said sleeve.

10. A looper mechanism having, in combination, an actuating eccentric, an eccentric strap, a looper mounted for loop-seizing and sidewise movements, means including a pin-and-sleeve sliding connection between said looper and eccentric strap for imparting to the looper its operative movements, one of the elements of said pin-and-sleeve connection being adjustably mounted on said eccentric strap so that its angle of inclination to the axis of said strap may be varied, and the other element of said connection being adjustable to conform to the first-mentioned element.

In testimony whereof, I have signed my name to this specification.

ANDREW B. CLAYTON.
